UNITED STATES PATENT OFFICE.

SAMUEL W. WHONN, OF SEATTLE, WASHINGTON, ASSIGNOR OF TWO-THIRDS TO NOYES MOULTON AND ONE-THIRD TO O. W. KELLOGG, BOTH OF SEATTLE, WASHINGTON.

EXTENSION-TABLE.

937,350.

Specification of Letters Patent.

Patented Oct. 19, 1909.

Application filed January 6, 1909. Serial No. 471,026.

To all whom it may concern:

Be it known that I, SAMUEL W. WHONN, a citizen of the United States of America, and a resident of the city of Seattle, in the 5 county of King and State of Washington, have invented certain new and useful Improvements in Extension-Tables, of which the following is a specification.

My invention relates to improvements in 10 tables of the above type and aims primarily to provide guide means of novel construction, adapted to support the bearing members of the adjustable table top sections.

A further object resides in the provision 15 of an improved construction wherein companion table top sections are connected for simultaneous movement.

Further objects will be set forth as my 20 description progresses and those features of construction, arrangements and combinations of parts, in which my invention resides, succinctly defined in my annexed claims.

Referring to the accompanying drawing, 25 wherein a preferred embodiment of my invention is illustrated: Figure 1 is a top plan view of my table in extended position, parts being broken away. Fig. 2 is a transverse section thereof. Fig. 3 is a fragmentary view, on enlarged scale, of one of the tracks 30 or guides. Fig. 4 is an edge view of one of the track or guide sections, and Fig. 5 is a detail view on enlarged scale, illustrating more particularly one of the link connections between the equalizing bar and an arm 35 of one of the table top sections.

In carrying out my invention, I provide a suitable frame 1, which may be of any desired construction. I preferably provide the same, however, with a bottom wall 2, 40 above which are arranged pairs of parallel supports 3, of wood or other suitable material. Supports 3 of each pair are spaced to receive therebetween the arms 4 of the table top sections 5, as clearly shown in Figs. 45 1 and 2.

To effect an equal adjustment of the table top sections 5, I provide an equalizing bar 6, pivoted at 7 to the bottom wall 2 of frame 1, and connected by links 8 to one of the arms 50 4 of each table top section. Links 8 instead of being pivoted directly to the said arms 4, are preferably pivoted to depending members 9, fixed to said arms (see Figs. 2 and 5).

Arms 4 are provided with edge flanges 4', 55 these being provided by suitably grooving

the sides of said arms, which flanges constitute bearing members for engagement with the upper and lower surfaces of tracks 10, provided on the opposing side faces of the respective supports 3 of each pair.

Tracks 10 are composed of sections 10' which are supported for swinging, by screws 11, which when tightened hold said sections against swinging. Track sections 10' are arranged end to end with suitable separation 65 and in horizontal alinement, see Fig. 3, and are provided with upper and lower edges or surfaces against which bear the bearing members 4' of arms 4. The sides of track sections 10' are inclined, as shown, whereby 70 the outer end of one active edge or bearing surface of a track section projects well beyond the inner end portion of the other thereof, thereby providing bearing portions 10^a, which upon adjustment of the track sections, can be moved outwardly, as indicated 75 by dotted lines in Fig. 3 to vary the width of the tracks.

By the construction illustrated, comparatively long bearing surfaces are provided on 80 the track sections, and they can be arranged close together and yet be capable of being swung, as found desirable.

The life of a track constructed, as described, will be of long duration, for wearing of the edge portions 10^a of the track sections and of the bearing members 4', which would result in play between said parts, and thereby permit the table top sections to sag, can be readily compensated 85 for by loosening screws 11 and swinging the track sections to move the portions 10^a outwardly, as previously described.

With the track sections thus adjusted, bearing members 4' will again snugly engage 95 the same and hold the table top sections 5 firmly.

Frame 1 can be supported as on a central standard, 12, in any desired manner.

Various changes can be made in the minor 100 details of construction, without departing from the spirit of my invention, as defined in my appended claims.

Having thus fully described my invention, what I claim as new and desire to secure by 105 Letters Patent of the United States, is:

1. An extension table comprising a frame, a table top section thereon, and means for supporting said table top section for adjustment on said frame including a track 110

- formed of independently adjustable sections arranged end to end.
2. An extension table comprising a frame, a table top section thereon, and means for supporting said table top section for adjustment on said frame including a track formed of swingingly supported sections arranged end to end.
3. An extension table comprising a frame, 10 a track thereon formed of swingingly supported sections arranged end to end, a table top section, and bearing means on said table top section arranged to engage the upper and lower edges of said track.
- 15 4. An extension table comprising a frame, a track thereon formed of sections arranged end to end, means supporting said track sections for independent swinging, said track sections being provided with upper and 20 lower bearing portions arranged to be moved
- in an outward direction upon swinging of the track sections, whereby the track will be increased in width, a table top section, and a bearing means on said table top section, arranged to engage the upper and lower edges 25 of said track sections.
5. An extension table comprising a frame, spaced supports thereon, tracks on said supports, said tracks being formed in pivoted sections arranged end to end, table top sections, arms secured to said table top sections, and bearing members on said arms engaging the upper and lower edges of said tracks. 30

Signed at Seattle, Washington this 23rd day of December 1908.

SAMUEL W. WHONN.
